SATURATING APPARATUS

Application filed September 5, 1928. Serial No. 304,103.

This invention relates to apparatus for impregnating absorbent fibrous sheets as for example, the felted fibrous sheets employed as a base for composition roofing material.

5 More particularly my invention is concerned with improved methods of saturation, wherein, the extent of saturation is carried to a point beyond the normal practice and wherein, the degree of saturation obtained 10 may be regulated within desired limits.

It will be appreciated by those skilled in the art, that it is desirable that the absorbent fibrous sheet constituting the base or foundation of the roofing be saturated as completely 15 as possible so as to not only completely cover or coat the individual fibers but to also fill the voids or interstices between the fibers with the saturant so as to thus lessen the capacity of the sheet to absorb water or moisture.

Improved methods have recently been adopted in the roofing industry for bringing about more complete saturation of the raw roofing felt than has hitherto been possible 25 in normal commercial practice, these improved methods as devised, being also adapted for controlling the extent of saturation so as to enable the manufacture to produce saturated sheets of substantially any 30 desired degree of saturation.

My invention concerns itself particularly with the aforesaid improved methods of saturation and has for one of its objects the provision of simplified means for carrying out 35 such a process. In carrying out my invention, I first immerse the sheet of felt in a bath of the saturant in substantially the same manner as is done in the prior practice but in withdrawing the sheet from the bath, I employ 40 a pair of squeeze rolls or draw rolls so arranged and having the sheet threaded therethrough in such a way, that excess saturant is squeezed from one face of the sheet therethrough and deposited upon the opposite 45 face of the sheet so as to leave the first named face of the sheet with substantially no excess thereon, while a substantial excess is thus deposited upon one face only of the sheet. Preferably the sheet may be then conducted 50 through a device for removing more or

less of this excess from the second face of the sheet, but leaving, however, a controlled excess thereon to be thereafter drawn or sucked into the interior of the sheet.

Various other objects and advantageous 55 features of my invention will be readily apparent from the following descriptions.

In the drawings,

Figure 1 illustrates somewhat conventionally an arrangement of apparatus for carrying out my invention;

Figure 2 is a plan view showing part of the mechanism of Figure 1;

Figure 3 is an enlarged detail view of the draw or squeeze rolls, illustrating the manner of threading the sheet therearound.

Referring in detail to the drawings, the numeral 20 indicates a roll of felt of the character commonly used in the asphalt roofing industry as the base or foundation for prepared roofing material. The felt from this roll is led over suitable guide rolls 21, into a bath of saturating material, such as low melting point asphalt, contained in the saturating tank 22, the sheet being passed 70 around guide rolls 23, similar to the guide rolls 21 and located near the bottom of the tank 22. Mounted adjacent the upper end of tank 22, opposite the point where the sheet enters the tank, are a pair of draw or squeeze 75 rolls 24, 25, arranged one above the other and driven from some suitable source of power in the directions indicated by the arrows. These rolls are adapted to propel the sheet through the tank and the bath of saturant contained 80 therein. As shown, the sheet passes first around the upper part of the upper roll 24, thence downwardly between the rolls and around the lower roll 25 from which point the sheet is then led to any suitable form of 85 mechanism for permitting it to cool. If desired, the upper draw roll 24 may be longitudinally and circumferentially grooved or corrugated in order to provide a roughened surface to further assist in propelling the wet 90 sheet from the saturating bath.

It will be seen, that as the sheet passes between the opposing surfaces of the rolls 24 and 25, excess asphalt remaining on the surfaces of the sheet as it leaves the tank 22 is 100

expressed from the surface B of the sheet which is in contact with the surface of the roll 24 through the sheet, leaving the sheet at the surface A, and falling downwardly 5 as indicated at F, to be received upon the surface A of the sheet as the latter passes beyond the lower roll 25. In this way, the sheet is in effect transformed at this point from a condition where it has excess on both of its 10 surfaces to a condition where substantially all of the excess is present on one of the surfaces only thus leaving the opposite surface with substantially no excess saturant thereon. In this condition the sheet may be more 15 readily cooled so as to absorb excess saturant from the first named surface, it being found that the cooling action progresses more rapidly and the saturant is absorbed to a greater extent by the sheet when the latter has excess on one of its surfaces only. 20

Generally, the sheet as withdrawn from the saturating bath has a greater excess of asphalt on its surface than can ordinarily be absorbed into the voids and pore spaces of 25 the sheet during the cooling action, and consequently, when substantially all of this excess becomes deposited on one surface of the sheet after the latter passes the squeeze rolls 24 and 25 as above described, the layer of 30 excess saturant on the surface A will be in excess of the maximum amount that can be absorbed into the interior of the sheet. It is desirable, that after the sheet has cooled to the required extent, no excess saturant remains on either of its surfaces, since such an 35 excess may lead to a slippage of the overlying protective coating of high melting point asphalt subsequently applied thereto in the manufacture of the roofing product, due to 40 the relative fluidity of the saturant material under the action of solar heat. At the same time, however, it is desirable to cool the sheet in the presence of such an excess of saturant on one of its surfaces as can be substantially 45 entirely absorbed into the voids thereof during the cooling action. Further, it is highly advantageous to control the amount of excess saturant remaining on the surface of the sheet so as to secure regulated degrees 50 of saturation. My invention includes mechanism for thus controlling the amount of saturant remaining on the surface of the sheet, the mechanism being susceptible of operation to secure almost any desired degree 55 of saturation, ranging from a saturating efficiency of 65 to 80% as normally obtained in the prior practice to an efficiency in excess of 90% and approximating the maximum capacity of the sheet to absorb saturant. 60 For this purpose I provide a tension or doctor blade 30, disposed transversely of the sheet and connected at its ends by the relatively short legs 31 to a parallel rod or bar 32, the sheet passing through the loop thus 65 formed and riding on the bar 32. The bar

32 is pivoted near its ends in the bearings 33, fixed to the supporting frames 34, and an operating lever 35 is secured at one end of the rod or bar 32 for swinging the blade 30 from the depending position it tends to assume by 70 its own weight. By properly manipulating the lever 35, the tension of the blade 30 upon the surface A of the sheet may be varied to thereby doctor off more or less of the excess saturant falling at F onto the surface A. By 75 thus regulating the tension of the bar 30 upon the surface A of the sheet, the amount of saturant that will remain on this face of the sheet as it passes beyond the bar 30, may be controlled within relatively narrow limits. 80 In order to thus control the tension of the doctor or tension blade upon the surface of the sheet, the handle 35 may have slidably arranged thereon, a counter weight 36 which may be fixed at any desired position along 85 the length of the handle as by means of a clamping device 37.

By arranging a counter weight at the proper point along the operating lever 35, a regulated excess of saturant will remain on 90 surface A of the sheet, and the sheet may then be conducted with this excess on the surface thereof to the usual festooning or looping mechanism 40 by which the sheet is supported in loops or festoons 41 and exposed to the atmosphere for sufficient length of time to enable the sheet to draw or suck in, by the attendant cooling action, the excess remaining on the surface, as already described. It will be seen, therefore, that by 100 my invention I provide simple means whereby the sheet is permitted to cool in the presence of a regulated excess of saturant on one of its faces, the regulation of such excess enabling the saturation to be carried on to 105 substantially any desired degree. From the looping mechanism 40, the saturated sheet may be led to the subsequent stages of operation, namely, the application of the waterproof protective coating and the surfacing 110 of mineral grit or other masking material, as will be understood by those skilled in the art.

Having thus described one embodiment of my invention it will be apparent that numerous variations and modifications may be made therein, without departing from its scope as defined in the claims hereunto appended.

I claim as my invention:

1. Apparatus of the character described, comprising a tank adapted to contain a supply of molten saturant, means for conveying a sheet of absorbent material into said tank, means for withdrawing the sheet from said tank and squeezing excess saturant therefrom onto one face of the sheet, means for removing some of said excess from said face, said last named means being controllable to leave a regulated residual excess thereon, and 120 125 130

means for permitting the sheet to cool in the presence of the said regulated excess.

2. Apparatus for saturating absorbent material, comprising a tank adapted to contain a supply of molten saturant, means for conveying a sheet of absorbent material into said tank, means for propelling the sheet through said tank, said propelling means being arranged to operate upon the sheet in such manner as to squeeze saturant from said sheet and discharge the same upon one face of the sheet as the latter passes beyond said propelling means, means for removing some of said saturant from said face, said last named means being controllable to leave on said face a regulated excess of saturant, and means for permitting the sheet to be cooled in the presence of said excess.

3. Apparatus for saturating absorbent material comprising a tank adapted to contain a supply of molten saturant, means for conveying a sheet of absorbent material into said tank, means for propelling the sheet through said tank, said propelling means being arranged to operate upon the sheet in such manner as to squeeze saturant from said sheet and discharge the same upon one face of the sheet as the latter passes beyond said propelling means, a doctor blade adapted to remove from said face some of the saturant thereon, means for regulating the tension of said blade upon the sheet whereby to leave on said face a controlled excess of saturant, and means for permitting the sheet to cool in the presence of said excess.

4. Apparatus for saturating absorbent material comprising a tank adapted to contain a supply of molten saturant, means for conveying a sheet of absorbent material into said tank, a pair of draw rolls exteriorly of said tank for withdrawing the sheet therefrom, the sheet being threaded around said draw rolls so as to squeeze saturant from said sheet and discharge the same upon one face of the sheet as the latter passes beyond said rolls, means for removing some of said saturant from said face, said last named means being controllable to leave on said face a regulated excess of saturant, and means for permitting the sheet to be cooled in the presence of said excess.

5. The method of saturating sheet material which comprises feeding the sheet into a bath of saturant, removing the sheet with an excess of saturant from the bath and subjecting it to a squeezing action whereby to cause excess saturant to be deposited upon one face of the sheet, while leaving the opposite face thereof substantially free of excess saturant, removing some of the excess saturant thus deposited upon the first named face whereby to leave thereon a regulated residual excess of saturant, and permitting the sheet to cool in the presence of said residual excess.

6. The method of saturating sheet material which comprises feeding the sheet into a bath of saturant, removing the sheet with excess saturant from the bath and subjecting it to a squeezing action whereby to cause substantially all of said excess saturant to be discharged onto one face of the sheet, removing some of the excess saturant thus discharged onto said face whereby to leave thereon a regulated residual excess of saturant, and permitting the sheet to cool in the presence of said residual excess.
